UNITED STATES PATENT OFFICE.

THOMAS A. KIDD, OF RAHWAY, NEW JERSEY.

BOILER.

SPECIFICATION forming part of Letters Patent No. 443,997, dated January 6, 1891.

Application filed December 16, 1889. Serial No. 334,006. (Model.)

To all whom it may concern:

Be it known that I, THOMAS A. KIDD, a citizen of the United States, and a resident of Rahway, in the county of Union and State of New Jersey, have invented certain new and useful Improvements in Boilers, of which the following is a specification.

My improvement relates to boilers for heating purposes, and I aim to produce a cheap and efficient heater which will be applicable in many cases where the high cost of existing apparatus prevents their use. I attain this by a simple mode of construction, which enables the heater to be put together very cheaply, and at the same time by the principle and combination of parts I obtain high heating efficiency. I secure this latter result by providing within the heater itself a primary circulation system so constructed and arranged that the upward or "flow" circulation-passages, or some parts thereof, shall be directly exposed to the fire, and by inserting in the course of the flow-passages a chamber or heater which has a large extent of surface proportionally to its volume and which is exposed directly to the flames. With the flow circulation-passages I combine downward or "return" circulation-passages, which are not directly exposed to the fire, and a water-reservoir, which is also to some degree protected from the full effect of the heat. These results, according to the well-understood principles of water-heating, a great preponderance of gravity in the return circulation-passages, which produces a very positive and energetic circulation of water through the heater. This circulation greatly promotes the rapid and economical heating of water and its conversion into steam. The aforesaid combination of a water-reservoir inside the heater, connected with the flow-passages, I have found to be very important, in order to prevent the intense heat from vaporizing all the water in the flow-passages or expelling the water therefrom and endangering the apparatus.

Referring to the drawings to aid the description, Figure 1 is a vertical section of the apparatus, showing the door to one side for the sake of clearness. Fig. 2 is a perspective elevation of the exterior. Fig. 3 is a plan of the top plate seen from above.

A is the base or ash-pit, constructed of cast-iron plates bolted together in the usual manner and containing the ash-door and dampers. On this base A is placed the water-reservoir B, which may be secured to the top plate of the base by bolts, and is in shape an annular vessel with an interior water-space B'. The vessel B may be constructed of cast-iron for the sake of cheapness. The said vessel B is placed on the base A so that it encircles and rises above the grate C. Thus the vessel B forms the lower part of the fire-pot. The grate C is of any usual form, and may be suspended on the base in any usual manner.

Into the top of the reservoir B is tapped a nipple b, threading into an elbow b', into which is threaded a nipple b'', which forms the lower extremity of a pipe-coil D. In some cases I find it advantageous to extend the nipple b nearly to the bottom of the reservoir B. The aforesaid coil D has a diameter across the coils somewhat less than the diameter of the reservoir B, so that a space is left between the coil and the fire-brick lining W for the free passage of the flames all around the coil D. The upper end of the said coil connects by an elbow d and nipple d', with the bottom of a spheroidal vessel E, which is cheaply formed by casting and is placed with its major diameter horizontal, and is directly over the grate C. This vessel E constitutes an auxiliary heater interposed in the course of the upward or flow circulation-passage, which passage is composed of the coil D, vessel E, and pipes connecting with the upper and lower reservoirs, and the said vessel E is shaped to have a great extent of heating surface proportionally to the volume of water which it contains. The upper part of the vessel E is connected by a threaded nipple with the lower part of the upper reservoir or steam-dome F, which is formed of cast-iron and has a flanged top plate G secured to the reservoir F by bolts, as shown. Return circulation-pipes H H are threaded into the lower part of the reservoir G and upper part of the reservoir B, as shown. Thus the coil D, heater E, and pipes H H form, together with the reservoirs B and F, a primary circulation system within the heater itself, of which the flow members D and E are exposed to the direct heat of the flames, while the return

members H H are to one side and not directly exposed to the flames, and are also protected by the fire-brick, as hereinafter set forth. Moreover, the reservoir B, by reason 5 of encircling the lower part of the fuel-space below the intense flames, and being also to one side of the fire, tends to preserve the water therein from the intense heat to which the coil D and heater E are exposed. Thus 10 there is produced a great preponderance of gravity in the return members H H and a positive energetic circulation of water through the heater. The vessel E being directly over the fire, steam is made energetically therein.

15 It is evident that in place of coils D and pipes H H, I may form the flow and return passages in other ways, the important parts of my invention being the combination of a heater E with the flow-passage, the placing 20 of the flow-passage and the heater E in direct exposure to the fire, and the removing of the return-passages from the like direct exposure.

From the top plate G of the reservoir F rises the steam-main I, with which are connected the branch pipes to the various radiators. (Not shown, and constituting no part 25 of my invention.) To this pipe I may also be connected pipes J and K, which also branch into the reservoir B, and to the said pipes 30 may be connected the usual safety-valve L, water-gage M, and pressure-gage N. The returns from the radiators may enter the reservoir B by a pipe O, and water may be supplied to the heater by a pipe branching into pipe 35 O, and not shown. With the reservoir B may also be connected pipes P and Q, rising to a damper-regulator R, by which the damper and check-doors may be controlled in the usual manner.

40 S is a blow-off valve.

The heater is inclosed in a jacket T, formed of sheet-iron and with double walls t and t' , forming a space u between, which may be filled with some non-conducting material, as 45 dry sand. The inner wall t' of the jacket T fits snugly under the flange g of the top plate G, the said flange extending across over the space u between the walls of the jacket T.

The outer wall t rises somewhat above the 50 top plate G, as shown, and the said plate is perforated with openings g' , placed to come directly over the space u . By means of these openings the jacket T may be filled with the non-conducting material, which may also be 55 spread over the plate G, as indicated by the dotted lines.

U is a fuel-door through the jacket T, having side walls to prevent the escape of the sand filling, and inside the door U is a chute

60 V to direct the coals to the interior of the coil D, whence they descend to the grate C. I prefer to line the jacket T with fire-brick

W, which are supported by the top of the reservoir B, and are placed so as to leave a space between the brick and the coil D for 65 the free passage of flames around the coil, as hereinbefore described. The bricks W are carried to a height equal to the height of the coil D, and they are extended to each side of the returns H H, so as to protect the said returns from the flames. There is of course a smoke-flue passing through the jacket T to 70 convey away the products of combustion.

W L indicates the water-level in the heater.

I claim—

1. In a steam-heater, a coil connecting a water-reservoir surrounding the fire-pot with a steam-dome, and a secondary heater between the steam-dome and the coil, connected directly with the coil, so that the circulation 80 from the water-reservoir to the steam-dome must pass through the coil and the secondary heater, as described.

2. In a steam-heater, the combination of a water-reservoir surrounding the fire-pot, a coil 85 ascending from the water-reservoir, a secondary heater between the steam-dome and the coil, connected directly with the coil, and a pipe connecting the secondary heater with the steam-dome, the whole arranged so that 90 the circulation between the reservoir and the dome passes through the coil and the secondary heater, as described.

3. In a steam-heater, the combination of a water-reservoir surrounding the fire-pot, a coil 95 ascending from the reservoir, a secondary heater directly connected with the coil and also with a steam-dome, and return circulation-pipes connecting the steam-dome with the water-reservoir, as described.

4. In a steam-heater, the combination of a lower water-reservoir surrounding the fire-pot, a coil rising from the reservoir, a secondary heater connected directly with the coil and placed vertically above the grate, so as to be 105 exposed to the full effect of the flames, a pipe connecting the secondary heater with an upper steam-dome, and return circulation-pipes connecting the steam-dome with the water-reservoir, as described.

5. In a steam-boiler, the combination of an outer jacket formed with double walls, and a flanged top having perforations placed to come over the space between the walls of the jacket, whereby the said space may be filled 115 with non-conducting material, as described.

Signed at New York, in the county of New York and State of New York, this 9th day of December, A. D. 1889.

THOMAS A. KIDD.
